GAME CASING

Derek J. Gay, Palos Verdes Peninsula, Calif., assignor to Mattel, Inc., Hawthorne, Calif.

Filed Feb. 26, 1970, Ser. No. 21,651

Term of patent 14 years

Int. Cl. D21—01

U.S. Cl. D34—5

FIG. 1

FIG. 2

FIG. 3

FIG. 4

FIG. 5

FIG. 1 is a perspective view of a game casing showing my new design;

FIG. 2 is a rear elevational view thereof;

FIG. 3 is an end elevational view thereof;

FIG. 4 is a top plan view thereof; and

FIG. 5 is a bottom plan view thereof.

I claim:

The ornamental design for a game casing, substantially as shown.
